UNITED STATES PATENT OFFICE.

ALFRED GABRIEL QUIRY, OF NEUILLY-SUR-SEINE, FRANCE, ASSIGNOR TO PIERRE JEAN ROBERT AMIARD, OF PARIS, FRANCE.

SOLDERING IRON.

1,416,508.

Specification of Letters Patent. Patented May 16, 1922.

Application filed March 26, 1921. Serial No. 455,821.

(GRANTED UNDER THE PROVISIONS OF THE ACT OF MARCH 3, 1921, 41 STAT. L., 1313.)

To all whom it may concern:

Be it known that I, ALFRED GABRIEL QUIRY, engineer, citizen of the French Republic, residing at Neuilly-sur-Seine, Department of Seine, France, have invented certain new and useful Improvements in Soldering Irons, (for which I have filed applications in France, Jan. 21, 1914, Patent No. 475,124; Germany, July 10, 1920; Great Britain, July 12, 1920, and Italy, June 17, 1920,) of which the following is a specification.

The object of the present invention is a soldering iron provided with means for adjusting the same at various angles relatively to a handle and supporting stem and represented by way of example in the accompanying drawings.

Fig. 1 a vertical section of the soldering iron in its normal position.

Fig. 2 represents, in a section, one of the positions the bit of the iron can occupy with respect to the handle.

Fig. 3 is a side view of a second position of the bit of the iron.

Fig. 4 is a partial vertical section along A—A in Fig. 1.

Fig. 5 is a horizontal section along B—B of Fig. 1.

The soldering iron forming the object of this invention consists essentially of a copper bit 1 the point 2 of which may be of any suitable form, whilst the rear part or heel has a blunted or cut side 3, and a mortise 4. This mortise can be lined on the inside with a sheet of nickel or other suitable material formed from a single piece so as to cover the walls of the mortise and folded or bent down on the outer sides of the rear part or heel of the copper bit.

The bit of the iron is fixed to a handle consisting of a central stem 6 terminating at the top with an eye 7 engaging in the mortise 4 and united with the bit by a pin 8 running through the two sides of the mortise 4 and the eye. This stem 6 is fitted inside a socket 9 the top part 10 of which is slightly enlarged or bulged formed with a flat supporting surface. The socket 9 penetrates to a certain extent into the wooden handle 11 of the iron and is secured therein by a binding screw 12 running through the ferrule 13, the handle 11 and a metal tube 14 inside the wooden handle 11. There is a transversal

pin 15 in a suitable part of the stem 6. This pin can work in elongated mortises 16 made in the extremity of the socket 9 which is lodged inside the wooden handle. This stem runs through the wooden handle and terminates at the lower extremity of this handle in a threaded part 17, on which a winged nut 18 resting on a washer 19 can be screwed. There is a spiral spring 20 inside the handle in the metal tube 14, the said spring bearing by one of its ends against the lower end of the socket 9 and by its other end against the washer 19.

It can easily be seen Fig. 1, that when the winged nut 18 is tightened, the iron is firmly maintained in the position represented in this figure owing to the tensile stress exerted by the nut on the stem 6, a stress which causes the bit of the iron to bear firmly against the upper flat supporting surface of the top part 10 of the socket 9.

To bring the bit from the position given in Fig. 1 to the position given in Fig. 2, it suffices after having loosened the nut 18 by a few turns to push back the stem 6 pressing on the threaded end 17 so as to bring pressure to bear on spring 20 and raise pin 15 in mortises 16; the bit by this means being free to move relatively to the flat top of the surface or seat of the upper part 10 of the handle 9 and permit the pin 8 to freely oscillate or pivot in the eye 7. It suffices to give the iron a certain incline downwards or rest the bit against some object to bring the said bit to the position represented in Fig. 2. When the change is made by pressing the bit against some object there is no need to press on the stem 6 to compress the spring, it suffices to loosen the nut 18. As soon as pressure is removed from the end of the stem 6, the spring 20 pulls the stem back and keeps the bit in the position to which it has been adjusted the nut 18 may then be readily tightened to fix the bit in its new position. A similar operation brings the bit to the position shown by Fig. 3.

Having now particularly described and ascertained the nature of my said invention and in what manner the same is to be performed, I declare that what I claim is:

1. A soldering iron of the class specified, comprising a stem, a tubular socket in which the stem is reciprocatingly mounted, a handle attached to the socket, and a bit

pivottally connected to the one end of the stem and having varying angular surfaces at the heel portion adjacent to the point of pivotal connection thereof to the stem to effect angular adjustment of the bit with relation to the end of the socket and means for sustaining the bit in its adjusted position.

2. A soldering iron of the class specified, comprising a supporting means with a flat end, a stem reciprocatingly mounted in the supporting means, a bit having a heel pivoted to the one end of the stem and movable in close relation to and adapted to be held fixed against the flat end of the supporting means, the heel of the bit being provided with bearing surfaces at angles to each other to positively engage the flat end of the supporting means, and means for releasing the bit for adjustment and for fixing the bit in its adjusted position.

3. A soldering iron of the class specified, comprising a supporting means consisting of a handle with a tubular socket projecting therefrom, a stem reciprocatingly mounted in the socket and provided with a screw-threaded extremity extending beyond the rear end of the handle, adjusting means engaging the screw-threaded end of the stem, a spring surrounding the stem in the handle and operating to retract the latter, the tubu-

lar socket having a flat end, and a bit provided with a mortise into which the stem projects for pivotal connection to the heel of the bit, the heel of the bit being formed with bearing surfaces at different angles to engage the flat end of the socket.

4. A soldering iron comprising a tubular handle, a tubular socket secured thereto and provided with a slot therein, a stem reciprocatingly mounted in the handle and socket and having a pin engaging the slot of the socket, means engaging the one end of the stem adjacent to the handle for fixing said stem against movement, the stem also projecting beyond the free end of the socket, and a soldering bit having a slotted heel to receive the projecting end of the stem for pivotal connection to the latter, the heel of the bit having angular surfaces to positively engage and be held against the adjacent end of the socket to dispose the bit at varying angles relatively to the socket.

In testimony whereof I have hereunto set my hand in presence of two subscribing witnesses.

ALFRED GABRIEL QUIRY.
